D. E. SCHRAEDLY

HANGER

Filed March 13, 1924

UNITED STATES PATENT OFFICE.

DAVID E. SCHRAEDLY, OF MANSFIELD, OHIO.

HANGER.

Application filed March 13, 1924. Serial No. 699,037.

To all whom it may concern:

Be it known that I, DAVID E. SCHRAEDLY, a citizen of the United States, residing at Mansfield, in the county of Richland and 5 State of Ohio, have invented certain new and useful Improvements in Hangers, of which the following is a specification.

This invention relates to a hanger which is principally adapted for use in supporting an eaves trough, in such a manner as 10 to enable the same to be securely supported on a roof, without having to employ nails or the like, for securing the hanger in position.

15 Another important object of the invention is to provide a hanger of the above mentioned character, which is of such a construction as to enable the same to be used for supporting various articles, the attaching means for supporting the hangers being 20 formed integrally therewith.

A still further object of the present invention is to provide a hanger of the above mentioned character, which is simple in 25 construction, inexpensive, strong and durable, and further well adapted for the purposes for which it is designated.

Other objects and advantages will become 30 apparent during the course of the following detailed description.

In the accompanying drawing, forming a part of this specification, and in which like numerals designate like parts throughout the same:

35 The figure is a side elevation of my invention.

In the drawing, wherein for the purpose of illustration is shown the preferred embodiment of my invention, the numeral 1 40 designates an elongated strand of wire, which has its intermediate portion looped as shown at 2 in the drawing, and the portion extending upwardly therefrom is then bent, as shown at 3, the bent portion being 45 directed laterally as illustrated at 4, and is then further bent back upon itself to extend in the opposite direction to provide the elongated arm 5 formed on the upper end of the strand of wire 1. The outer free end 50 of the arm 5 is pointed to provide a means for enabling the hanger to be conveniently supported or attached in position, as will hereinafter be more fully described. The portion of the strand of wire 1 below the 55 loop 2 is twisted as illustrated at 6, in the drawing, for a suitable distance. The lower

end of the strand of wire 1 is bent outwardly in one direction, and is then curved as shown at 7, and terminates into the upwardly extending end 8, which is substantially arranged on the upper side of the strand of wire.

An additional strand of wire 9, which is intertwined with the twisted portion 6 of the strand of wire 1, has its upper end provided with a bent portion 10, and the latter has an arm 11, similar to the arm 5 herefore described, bent back upon itself and extends through the looped portion 2 of the strand wire 1, in a manner as clearly 70 shown in the drawing, and is also provided at its outer free end with a sharpened point, for the same purpose as the arm 5. A pair of arms are thus provided, which will obviate the necessity of having to use nails 75 or the like, in securing the hanger in position, the sharpened points of the arms being driven into the supporting structure.

The looped portions of the arms forming heads whereby the hammer or the like may 80 be employed for driving the pointed ends of the arms into the supporting structure.

The lower end of the second strand of wire 9, directed on the opposite side of the strand of wire 1, and is disposed in opposite 85 directions to the outwardly extending portion of the lower end of the strand of wire 1 as is clearly shown in the drawing. The lower end 12 of the strand of wire 9 is provided with the looped portion 13 which 90 engages the free end 8 of the curved portion 7 of the strand of wire 1, and a similar looped portion 14 is swung in the lower end 12 of the second strand of wire 9 for inter-engagement with the outwardly directed portion of the lower end of the first mentioned strand of wire 1. It is to be understood that the free end of the lower end 12 of the second strand of wire 9, is twisted 95 around the looped portions formed therein 100 so as to securely hold the loop portions in their proper positions.

In use, the loop portions 13 are disengaged from the free end 8 and the article to be supported is disposed within the curved portion 7 of the strand of wire 1. As is readily seen from the drawing, the curved portion 7 is preferably adapted to conform to the contour or shape of an eaves trough, but it is to be understood that the curved portions may be of such 110 design as to enable the same to be readily

- used in conjunction with supporting any other article, and I do not wish to limit myself to the particular design or construction of the article supporting means.
- 5 The looped portion 13 is then placed over the free end of the end 8 whereby the article supported in the curved portion 7 will be securely held therein. The upper end of the hanger is then driven into the supporting structure in the manner as heretofore described.

It will thus be seen from the foregoing description, that a hanger has been provided, which is very simple in construction, 15 inexpensive, and will furthermore enable the article to be supported at such a position as to prevent the same from accidentally becoming disengaged therefrom. The simplicity of my device enables the same to be 20 easily and readily disassembled whenever necessary, and does not require the use of any complicated tools or the like, in order to place the same in use.

While I have shown the preferred embodiment of my invention, it is to be understood that various changes in the size, shape and arrangement of parts may be resorted to, without departing from the spirit of the invention and the scope of the subjoined 30 claims.

Having thus described my invention, what is claimed is:

1. A hanger of the class described, comprising a pair of elongated wires, one of 35 said wires having the intermediate portion

thereof provided with a loop, the upper end of said wire being disposed outwardly to provide attaching arms, the other wire having its upper end disposed outwardly in the same direction as the beforementioned attached arm, and adapted to extend through said loop, and forming an additional attaching arm, the body portions of said wires being inter-twisted and having the lower ends thereof disposed outwardly 45 in opposite directions and adapted to conform with the shape of the article to be supported thereby.

2. A hanger of the class described, comprising an elongated strand of wire looped 50 intermediate its ends, the upper end thereof being disposed outwardly to provide an attaching arm, the body portion of said strand of wire below said loop being twisted, the lower end of said wire extending 55 outwardly and being conformed with the shape of the article to be supported thereby, an additional wire being inter-twisted with the twisted portion of said first mentioned wire, the upper end of said additional wire being disposed outwardly 60 in the same direction, as the before mentioned attaching arm, and being disposed through said loop to provide an additional attaching arm, the lower end of the additional wire forming a clamping means for the lower end of said first mentioned wire.

In testimony whereof I affix my signature,

DAVID E. SCHRAEDLY.
